[57] **CLAIM**

The ornamental design for a combined cassette dictating machine and microphone therefor, as shown and described.

DESCRIPTION

FIG. 1 is a top front perspective of a combined cassette dictating machine and microphone therefor, showing my new design;

FIG. 2 is a top front perspective thereof; with the microphone in a restored position and the cassette closure open;

FIG. 3 is a top front perspective as seen from the side opposite FIG. 1 and with the microphone omitted for ease of illustration; and

FIG. 4 is a top rear perspective of FIG. 2.

Fig.2
